UNITED STATES PATENT OFFICE.

LEONARD MERRITT LIDDLE, OF PITTSBURGH, PENNSYLVANIA, ASSIGNOR TO
ANDREW JERGENS COMPANY, OF CINCINNATI, OHIO, A CORPORATION OF
OHIO.

SOAP.

1,377,843.

Specification of Letters Patent. Patented May 10, 1921.

No Drawing.

Application filed July 7, 1919. Serial No. 309,080.

To all whom it may concern:

Be it known that I, LEONARD M. LIDDLE, a citizen of the United States, residing at Pittsburgh, in the county of Allegheny, 5 State of Pennsylvania, have invented certain new and useful Improvements in Soap; and I do hereby declare the following to be a full, clear, and exact description of the invention, such as will enable others skilled in 10 the art to which it appertains to make and use the same.

This invention relates to improvements in the manufacture of soap which is neutral or nearly neutral or even acid or superfatted in 15 character and which contains an alkali metal salt of a weak organic acid of low molecular weight, for example, sodium or potassium acetate or lactate.

The present invention is based upon the 20 discovery that increased hardness or improved detergent properties, or both increased hardness and improved detergent properties, can be imparted to soap by the incorporation therein of an alkaline metal 25 salt of one of the lower alifatic acids; and that such salts are also advantageous as a filling for making filled soap.

It is well known that not every oil and fat 30 will yield a soap fulfilling the demands made upon it for household, toilet and manufacturers' purposes; and it is customary, in the soap-making art, to blend the different oils or fats available in such a manner as to produce a soap which is most suitable 35 for the intended purpose. In general oils and fats of low titer give soft soaps, and hard fats of high titer give hard soaps; and it is common practice to blend oils and fats, depending upon the titers of the different raw materials, to give a composite mixture having the desired titer and which 40 will give a soap of the proper hardness.

According to the present invention, oils and fats which are not themselves adapted 45 to give a soap of proper hardness may have the proper degree of hardness imparted thereto without the admixture of hard fats and without the incorporation therewith of strong alkaline substance such as soda ash, 50 borax or sodium silicate.

In the manufacture of soap from natural oils and fats by means of caustic soda, it is customary to use an excess of soda in order

to bring about complete saponification of the neutral fat or oil. As a result, there is 55 an excess of caustic alkali present in the soap at the end of the soap-making reaction. In order to remove as much as possible of this excess alkali, it is customary to salt out the soap and separate the soap curd from 60 the aqueous layer containing the salt, glycerin and excess caustic soda, and to retreat the soap curd by boiling it up with fresh amounts of water, and again salting it out to separate further amounts of alkali there- 65 from. Nevertheless, the finished soap produced in this way will usually still contain a small amount of excess alkali, and even the highest grades of soap upon the market will usually contain small amounts of this ex- 70 cess alkali. This small amount of alkali may not be objectionable for many purposes, but it can, nevertheless, be entirely removed, and, at the same time, improved properties 75 imparted to the soap, according to the present invention.

In the manufacture of laundry and other soaps, it is customary to incorporate with the soap varying amounts of alkali salts, such as soda ash, borax or sodium silicate. 80 These salts, however, have a strong alkaline reaction and the soap containing them is injurious to sensitive skins and to delicate silk and woolen fabrics. According to the present invention, the presence of such alkaline 85 reagents is avoided, and the soap is made of a neutral or nearly neutral character, while it is, nevertheless, given improved detergent and other properties, comparable with the properties of soap containing the strong 90 alkaline salts above referred to, without the objectionable alkalinity of such soap.

According to the present invention there is incorporated with the soap, at a suitable stage of the soap-making process, a sufficient 95 amount of a salt of one of the lower fatty acids, such as sodium acetate or sodium lactate, to impart to the soap the desired properties, such as increased hardness or improved detergent properties, or to provide 100 the soap with a suitable filling. The soap with which such alkaline metal salts of the lower alifatic acids are compounded, is itself of a neutral or nearly neutral or even acid character; that is, it is free, or nearly free, 105 from any excess alkali, and it is likewise

free from any added alkaline salts having a strong alkaline reaction, such as soda ash, borax or sodium silicate. The excess alkali of the soaps of the present invention will not generally exceed a small fraction of one per cent., for example, about 0.3 of alkali, figured as soda ash. Such a small amount of alkali is unobjectionable for many purposes, but the soap may even be freed from this slight excess of alkali, according to the present invention, so that it will be neutral. The soap may also be of an acid character, due to the presence of a slight excess of fatty acids.

15 The addition and incorporation of the sodium acetate or lactate, or like salt, will usually be effected after the soap-making process has been nearly completed. Thus, in the usual process of making finished soap, 20 the sodium acetate may be incorporated with the soap during the usual crutching operation, after the soap has been freed from the excess alkali, and after it has been permitted to stand for the separation therefrom of 25 the nigre. The sodium acetate may thus be added to the finished soap in the soap crutcher, together with a small amount of water, or with varying amounts of water, depending upon the amount still 30 present in the soap and the amount which it may be desired to incorporate in the finished soap. The addition of the sodium acetate makes possible the incorporation of a somewhat increased amount of 35 water when this is desirable. The incorporation of the sodium acetate will also serve to increase the hardness of the resulting soap, so that soaps of the desired hardness can thus be made from starting materials 40 which, without the addition of the sodium acetate, would give a soap objectionably soft.

In the common soap-making process, as above stated, varying amounts of excess alkali will usually be present in the finished soap. In transparent soap or in soaps made by the cold process, if precautions are not taken to avoid excess of alkali in the finished soap, a considerable amount of alkali may be 45 present therein. This excess alkali may, with advantage, according to the present invention, be neutralized by adding thereto acetic acid in amounts corresponding to the excess alkali, so that it will combine there- 50 with and form the alkali metal acetate, for example, sodium acetate, where caustic soda is used as the alkali in the soap-making process. This method of incorporating sodium acetate with the soap has the added 55 advantage of reducing or entirely removing the excess alkali, so that the finished soap is neutral in character.

60 For transparent soaps, it is common to use the finest grades of soap material and 65 pure strong lye and to add alcohol at the

end of the saponification and leave the glycerin with the finished soap, so that the finished soap will remain alkaline in character. This excess alkali can with advantage be left in the soap and neutralized therein by the 70 addition of sufficient acetic acid in the manner above referred to, so that the transparent soap will retain all of its usual ingredients, but will have its excess alkali neutralized by the added acetic acid, so that the soap 75 will be given improved properties, due to the sodium acetate. This sodium acetate will increase the hardness of the soap without destroying its transparency, if the amount of sodium acetate is not too large, 80 and the detergent properties of the soap will at the same time be improved. For slight hardening of transparent soap one or two per cent. of sodium acetate or sodium lactate will have an appreciable hardening effect. 85 This amount, however, may be somewhat increased to increase the hardness or the detergent properties.

A transparent soap may thus be made from a mixture of about 50 per cent. of tallow, 30 per cent. of cocoanut oil and 20 per cent. of castor oil. If too much water is added during the soap-making process, the resulting soap will not harden or set, but it can be readily made to harden by the addition of a small amount of sodium acetate, and the resulting soap will still be of a transparent character and retain as usual its content of glycerin and the added alcohol.

In general, I regard sodium lactate as 100 more advantageous for use in transparent soap, for the reason that it is less likely to crystallize out, and apparently has more valuable properties in promoting the transparency. I have found soap containing sodium lactate to be more transparent than soaps containing equal quantities of sodium acetate.

In the manufacture of soap powders, it is customary to use a relatively hard fat so 110 that the resulting soap powder will be hard enough without requiring added hardness to be imparted thereto. The compounding or incorporating therewith of sodium acetate will, nevertheless, increase the detergent 115 power of the soap powder. Moreover, a softer fat, or a fat of lower titer can be used in making the soap powder, and increased hardness can be imparted thereto by the addition and incorporation of sodium acetate. 120 The sodium acetate may be added to the soap before it is finally solidified, and this is desirable where the soap is not itself sufficiently hard without the addition of the sodium acetate. If the soap is itself suf- 125 ficiently hard, the sodium acetate may be ground together with the soap at the time the soap powder or washing powder is produced. Soap powders may thus be made by grinding together pure soap and sodium 130

acetate in varying portions up to as much as 35 per cent. or more of sodium acetate and 65 per cent. or less of pure soap.

The soap can be made in other forms than 5 the form of soap powder; for example, in the form of flakes, by incorporating the sodium acetate or a solution thereof with the soap prior to the flaking operation.

In the manufacture of soap it is common 10 to add varying amounts of rosin, so that rosin soaps are present in the final soap products. Rosin soaps frequently become soft and runny, and may require special treatment to overcome this tendency. According 15 to the present invention such soaps can be readily hardened, and their detergent property at the same time increased, by adding a sufficient amount of sodium acetate, or other suitable salt, to give the 20 desired hardness.

The present invention also provides an improved means for filling soap and for making filled soap, where such soaps are desired. The sodium acetate, for example, 25 can be added in a solution of suitable strength and in sufficient amounts.

In the manufacture of liquid soap, such as is used, for example, for shampooing and in liquid soap dispensers, it is common to 30 add alkali salts having a strong alkali reaction, for example, soda ash, borax or sodium silicate. Such alkali salts increase the lathering properties of the liquid soap, but they are objectionable because of their strongly 35 alkaline reaction, and if present in any considerable amount, may result in an objectionable "dryness" of the skin or of the hair brushed or shampooed therewith. According 40 to the present invention, such objectionable alkalinity is avoided, and liquid soaps are, nevertheless, given improved detergent and lathering properties, while still retaining them of a neutral or nearly neutral or even slightly acid character. 45 The liquid soaps of the present invention are thus of particular value for use in shampooing and in liquid soap dispensers. Inasmuch as the addition of sodium acetate or like salt will serve to harden the soap, it 50 may be necessary to add further amounts of water to prevent its solidification. Even concentrated solutions of the liquid soap can, nevertheless, be freely used without injury to even tender skins or to delicate 55 fabrics.

The amount of sodium acetate or lactate can be varied within rather wide limits. In some soaps, where a slight hardening is desired, as little as one or two per cent of 60 sodium acetate will materially assist in the hardening. For many purposes, however, an addition of as much as five to ten per cent. or more of sodium may be desirable. If the soap without the addition of the sodium acetate would be objectionably mushy 65

or slimy, a few per cent. of the sodium acetate will usually suffice to convert the material into a soap of the desired hardness. Where the sodium acetate is to be added as a filling or to increase the detergent power, 70 as in laundry soaps and soap powders, as much as thirty per cent. or more may be added to the soap composition. The sodium acetate or lactate or other salt can be added in a dry state, as in the production of a soap 75 or washing powder by grinding the dry sodium acetate with the soap, or where the soap already contains the desired amount of water. It can also be added in the form of a solution of varying strength. A solution containing about thirty or forty per cent. of sodium acetate will have an effective hardening action upon the soap to which it is added. In the production of liquid soap, the water which may be added 80 as a solvent of sodium acetate or otherwise should be sufficient to keep the amount of sodium acetate added from hardening or solidifying the soap, and thereby preventing it from remaining in a liquid form. 85

In general, sodium salts of the lower aliphatic acids, such as sodium acetate or lactate, should be added to soda soap, and potassium salts should be added to potash soap. Thus, for example, potassium acetate, or 90 other potassium salts, should be added to a high grade potash soap, such as a potash shaving soap, and similarly sodium acetate or other sodium salt should be added to the common soda soap, so that the alkali metal 95 of the added salt and of the soap itself will be the same.

The soap compositions of the present invention, can, of course, be compounded with other ingredients, such as perfume or coloring matter, or ingredients which will adapt the soap for special purposes. There may thus be compounded with the soap, material such as chalk, barytes, sand and the like, which will serve to adapt the soap as a 100 scouring soap; or naphtha, petroleum or tar oils, may be incorporated with the soap, to form naphtha soap, petroleum soap, or tar soap.

Inasmuch as the alkali metal salts of the 115 lower fatty acids which are employed in the soap compositions of the present invention are free from any objectionable alkaline reaction, the resulting soaps are well adapted for use for various purposes, where the presence of alkali is objectionable. They are thus well adapted for ordinary washing purposes, without injury to even the most sensitive skins or to the most delicate silk and woolen fabrics. The soap of the present 120 invention is, accordingly, well adapted for use where the highest grades of pure soap are now used, and it presents the advantage over such pure soap of increased detergent properties. It is thus comparable in its 130

detergent properties to soaps containing corresponding amounts of strong alkalis, such as soda ash or sodium silicate, while it is free from the objectionable alkaline properties of such soaps.

The alkali metal salts of the lower aliphatic acids are salts of a strong base and of a weak organic acid of low molecular weight. They are, nevertheless, neutral in reaction,

- 10 in the sense that they do not have any such alkaline reaction as do inorganic salts, such as soda ash, borax or sodium silicate. In fact, these alkali metal salts of the lower aliphatic acids themselves partake of the nature of soaps, inasmuch as the soaps are likewise alkali metal salts of fatty acids. The soaps themselves are, however, distinguished from these alkali metal salts of the lower aliphatic acids by the fact that they are made
- 15 from higher fatty acids having a characteristic greasiness, and a relatively high molecular weight; whereas, the lower fatty acids are free from the characteristic greasiness of the higher fatty acids, and their salts
- 20 are free from the characteristic soap consistency and solutions of the salts from the colloidal character of strong soap solutions.

From the foregoing description it will be evident that the present invention is of general application to the soap-making art and that soaps of various kinds and for various purposes may be made in accordance therewith. Soaps can thus be made in various forms, such as in the form of soap powder

35 or flakes, or in cake or liquid form, or in the form of paste, such as tooth paste, etc. The soaps may be such as are commonly used for household or toilet purposes, or they may be such as are used in laundries or

40 in other manufacturing plants where treatment with soaps of various kinds is required, as in the treatment of textiles and the like.

The soaps of the present invention, irrespective of the purpose for which they are to be used, present the characteristic advantages of freedom from any appreciable amount of free alkali and improved detergent properties. In addition the soap may have an increased degree of hardness imparted thereto

45 by the added sodium acetate or other salt, or

the soaps may be filled with such salt. The present invention, accordingly, includes soaps of various kinds which contain in an appreciable amount sodium acetate or lactate or salts of a similar character, irrespective of whether the salts are added to impart hardness or to improve the detergent properties, or as a filler, or for two or more of these purposes.

I claim:

1. A solid soap composition of a neutral or nearly neutral character, comprising soap and an alkali metal salt of a lower aliphatic acid.
2. An improved solid soap composition free from any appreciable excess alkali or compounds of a strongly alkaline reaction and having improved detergent properties imparted thereto by the incorporation therewith of an alkali metal salt of a lower aliphatic acid.
3. A solid soap composition comprising soap normally soft in character and having hardness imparted thereto by the incorporation therewith of an alkali metal salt of a lower aliphatic acid.
4. A solid soap composition comprising filled soap having as a filling therefor an alkali metal salt of a lower aliphatic acid.
5. A soap powder comprising soap and an alkali metal salt of a lower aliphatic acid, said soap powder being free from any appreciable excess of alkali or compounds of a strong alkaline reaction.
6. A solid soap composition comprising substantially pure neutral or nearly neutral soap and alkali metal salt of a lower aliphatic acid.
7. A transparent solid soap of a neutral or nearly neutral character, containing an alkali metal salt of a lower aliphatic acid.
8. Soap compositions of the character referred to in the preceding claims in which sodium acetate is the alkali metal salt.

In testimony whereof I affix my signature.

LEONARD MERRITT LIDDLE.
